UNITED STATES PATENT OFFICE.

GEORGE BURNELL AND ARTHUR BURNELL, OF HINDMARSH, SOUTH AUSTRALIA.

APPARATUS FOR CLEANSING WOOL.

SPECIFICATION forming part of Letters Patent No. 440,418, dated November 11, 1890.

Application filed October 9, 1888. Serial No. 287,699. (No model.)

To all whom it may concern:

Be it known that we, GEORGE BURNELL and ARTHUR BURNELL, wool-staplers, subjects of the Queen of Great Britain, residing at Hindmarsh, in the Province of South Australia, have invented an Improved Apparatus for Cleansing Wool and other Textile Products, of which the following is a specification.

The object of our invention is to provide an apparatus for manipulating wool and other similar textile products during a process of cleansing in which use is made of a volatile solvent—such as benzine—for the purpose of extracting the grease, yolk, and other oils or salts, as potash, &c. The advantage of employing this class of solvents is that the "wool" (in which term both here and hereinafter we include all other similar materials) is cleansed from all impurities, including sand and earthy matters, except seeds or burrs, without tearing and tangling the fibers or breaking up the fleeces.

The process for the carrying out of which our apparatus is designed consists in passing greasy wool through benzine, and subjecting it, during such passage and while in the solvent, to repeated squeezings for the purpose of removing the grease and earthy matters. The latter, being precipitated during the process of the operation, are removed by an automatic appliance, and on the solvent becoming saturated with the grease and yolk it is removed for their recovery by further treatment. After eliminating as far as possible the benzine by final suppression, the process further consists in passing the partially-cleaned wool through water for the purpose of removing the potash and other similar substances soluble in water. During such passage, and while in the water, the wool is again subjected to repeated squeezings, and, after a final compression, by which as much as possible of the liquid is removed, is delivered for drying free from all impurities except seeds or burrs.

Our apparatus consists of a receptacle or pair of tanks, each provided with a revolving drum and a series of rollers compressed by springs upon the circumference of the drums. Additional rollers are also provided for the final elimination of the solvents and for the

transit of the wool during the progress of the operation, while the tank containing the benzine is constructed with an apparatus for the automatic removal of the heavier impurities precipitated during the process.

In order that our invention may be better understood, we will now proceed to describe the same by reference to the accompanying drawings, in which—

Figure 1 is a longitudinal elevation, partly in section, of the apparatus complete, the outer casing being removed in order to more clearly show the internal mechanism. Fig. 2 is an end sectional elevation of the main tank, taken on the line 2 2 of Fig. 1. Fig. 3 is a side sectional elevation, showing the end of a squeezing-roller with bearing-block and actuating-spring, the flange of the main drum and teeth of gear-wheels; Fig. 4, an end elevation of squeezing-roller and attachments; Fig. 5, a side elevation of end-compressing rollers, showing spring-attachment for straining them together; Fig. 6, an end elevation of compressing-rollers and spring-attachments.

Referring to Figs. 1 and 2, where are shown longitudinal and cross-sections of an apparatus consisting of two tanks or receptacles for solvents and mechanism for treating the wool, A is a drum or roller, constructed, preferably, with cast-iron flanges and having its circumference covered with sheet metal; A', spindle of the drum A, revolving in suitable bearings provided in the main frame-work, and actuated by a main driving-pulley; A², deep flanges of the drum A, Figs. 1, 2, and 3.

A² are toothed flanges or gear-wheels for actuating the subsidiary rollers. The toothed flange A³, in actual practice, is constructed in one piece with the flange A².

B is a second drum of similar construction to the drum A, but of smaller size; B', spindle of the drum B, revolving in suitable bearings provided in the main frame-work.

B² are deep flanges of the drum B. The flanges B² are constructed with further toothed flanges similar to the flanges A³, but which are not shown in the drawings.

C C, Figs. 1, 2, 3, and 4, are subsidiary rollers of such length as to revolve freely between the flanges A² or B²; C', spindles of same.

C^2 are toothed wheels or disks attached to the rollers C on alternate ends and geared into the flanges A^3 , by which they are driven. The rollers C, connected with the smaller drum B, are provided with similar gear-wheels. (Not shown in the drawings.)

D D are adjustable bearing-blocks of spindles C', Figs. 1, 3, and 4; D' D', guide-blocks for the bearing-blocks D, dovetailed into the rim of main frame-work; E E, spiral springs fitting into a recess in each block D, and taking a bearing on the rims of the tanks, Figs. 3 and 4, for the purpose of compressing the rollers C against the circumferences of the drums A and B; F F, carrier-rollers for conveying the wool under treatment from one tank to another; F' F', gear-wheels for driving carrier-rollers.

G G, Figs. 1, 5, and 6, are wringing-rollers covered with cloth or other elastic material, and of such length as to revolve freely between the flanges A^2 or B^2 . The rollers G G strip the wool from the rollers A and B.

G' are spindles of the rollers G, revolving in suitable bearings in the main frame-work; G², smaller wringing-rollers; G³, bearings for spindles of the rollers G; G⁴, bearings for spindles of the rollers G²; G⁵, spiral springs connecting the bearings G³ and G⁴.

H H are scraping-rollers actuated by any suitable means and provided for the purpose of preventing the wool from wrapping around the wringing-rollers G.

I I are feed-rollers connected to gear-wheels and forming the entrance of the machine. A tip of leather or other suitable material i is in close contact to the rollers at the inlet and outlet, so as to prevent as much as possible the escape of the fumes from the solvent.

J is a feed-apron or endless band for conveying the wool to the mouth of the machine; K, bracket supporting the feed-apron J, bolted to one of the main supports; L, Figs. 1 and 2, grooved roller for removing the sand and earthy impurities; L', spindle for the grooved roller L, revolving in suitable bearings and driven from the main spindle A'; M, cylinder-casing of the roller L, bolted to the main frame-work of the first tank; N N, deep longitudinal

grooves in the roller L; P, opening or slot in the main tank leading to the grooved roller L; Q, trap-door hinged to the casing M, forming the outlet of the earthy impurities, and closed, as shown, when the machine is at rest,

55 in order to prevent the escape of the solvent; T T, tanks containing the solvent; U U, cast-iron supports; V V, cover of tanks T T; W, escape-pipe of fumes from solvent; X, delivery-apron or endless band on which the wool

60 is received from the final wringing-rollers G G² and carried to the drying-room for final treatment.

The modes of cleansing wool and removing the precipitated earthy matters by means of our apparatus is as follows: The first or larger tank is partially filled with benzine to the dotted line, (marked solvent), as shown. The

second or smaller tank is partially filled with water to the dotted line of water, as shown. On the machine being set in motion by moving the main driving-belt the wool spread upon the feed-band J is conveyed in a continuous stream to the feed-rollers I. By these it is seized, and being carried into the machine is passed onto the circumference of the drum A. As the drum A revolves in the direction shown by the arrows, the toothed flange A^3 engages the gear-wheels C² and turns the rollers C in the reverse direction, as shown by the arrows. The wool, being carried round by the drum A, receives repeated squeezings as it passes between the rollers C, which are compressed sufficiently for this purpose by the action of the spiral springs E on the adjustable blocks D, which carry the spindles C'. As an effect of the solvent, together with these repeated squeezings during its progress through the solvent, the grease and earthy impurities are gradually eliminated. The grease is held in partial suspension by the solvent; but the heavier particles are precipitated to the bottom of the tank and fall through the opening P into the grooves N of the roller L as the latter slowly revolves in the cylindrical casing M. Means are also provided by a tap or otherwise for the removal of the saturated solvent for recovery of the by-products by evaporation and condensation of the solvent through any known process. The wool, becoming cleaner and cleaner through the repeated squeezings in the solvent, is carried round to the wringing-rollers G G² and passes between them. The rollers G², being drawn tightly against the circumference of G by the springs G³, wring out almost the whole of the solvent and pass the wool onto the carrying-rollers F, ready for the second part of the process. To prevent the wool wrapping round the roller G, a stripping-roller H is provided. The carrier-rollers F, connected by the gear-wheels F', pass the wool along their upper surface to the second tank and deliver it onto the circumference of the drum B. The second tank is filled with water at a suitable temperature, in which the wool is again subjected to repeated squeezings by the rollers C, as before. By this further process the potash and other impurities soluble in water are removed. The wool is meanwhile carried round to the second set of wringing-rollers, which have a similar action to the first set. Here it receives a final compression in order to free it from the water as much as possible, and being lifted from the roller G by the stripping-roller H is delivered onto the endless band X for carriage to the drying-chamber.

The apparatus is rendered vapor-proof as much as possible by suitable tips or coverings at the entrance and exit of the wool, and is besides provided with an exhaust W, through which the fumes of the solvent given off during the cleansing operation are carried for condensation and further use.

We wish it to be distinctly understood that we do not confine ourselves to the particular number of tanks composing the apparatus or to the combination of two or a series in one machine; nor do we confine ourselves to any particular number of the rollers C or the method of compressing the same on the drums A and B, nor to any particular number of grooves in the roller L; but

10 We claim as our invention—

1. A machine for cleansing wool or the like, consisting of a vapor-tight receptacle comprising two tanks, the first to contain a solvent and the second to contain water, each tank provided with squeezing devices, wringing-rollers to retain the solvent in the first tank, guide-rollers between the tanks, rollers

at the entrance and exit, and leather tips to keep the receptacle vapor-tight, as and for the purpose set forth.

20

2. In a machine for cleansing wool and the like, the combination of a tank containing a solvent with a cylindrical casing attached to the tank and a grooved cylinder revolving in the casing, and a door hinged to the casing, 25 as and for the purpose set forth.

In witness whereof we have hereunto set our hands in the presence of two witnesses.

GEORGE BURNELL.
ARTHUR BURNELL.
